INVENTOR.
Herman C. Maise
BY *William H. Whittemore*

ATTORNEY.S

Patented Oct. 6, 1925.

UNITED STATES PATENT OFFICE.

HERMAN C. MAISE, OF DETROIT, MICHIGAN, ASSIGNOR TO BRIGGS MANUFACTURING COMPANY, OF DETROIT, MICHIGAN, A CORPORATION OF MICHIGAN.

WEATHER-STRIP-ASSEMBLING MACHINE.

Application filed October 8, 1923. Serial No. 667,424.

To all whom it may concern:

Be it known that I, HERMAN C. MAISE, a citizen of the United States of America, residing at Detroit, in the county of Wayne 5 and State of Michigan, have invented certain new and useful Improvements in Weather-Strip-Assembling Machines, of which the following is a specification, reference being had therein to the accompanying drawings.

This invention relates to machines and refers more particularly to those having means for attaching weather strips to molding and the like.

An object of the invention is to provide 15 a simple and efficient machine having means for supporting molding of various lengths and having means for easily and quickly attaching weather strips of various lengths to the molding.

Another object is to provide a machine 20 having means for separating portions of the weather strips and having means for guiding the weather strips into the path of the attaching means.

Another object is to provide a machine 25 in which the molding is automatically ejected from the supporting means after the weather strips have been attached to the molding.

With the above and other objects in view, 30 the invention consists in certain novel features of construction, combination and arrangement of parts as will be more fully described and particularly pointed out in the appended claims.

In the accompanying drawings:

Figure 1 is a top plan view of a machine embodying my invention;

Figure 2 is a sectional view taken on 40 line 2—2 of Figure 1;

Figure 3 is a sectional view taken on line 3—3 of Figure 1;

Figure 4 is a fragmentary side elevation 45 of the machine embodying my invention;

Figure 5 is a fragmentary cross sectional view through the machine embodying my invention and showing the molding applied to the support;

Figure 6 is a fragmentary cross sectional 50 view through the machine and showing the weather strip applied to the molding carried by the support;

Figure 7 is a detail fragmentary perspective view of the molding and weather strip attached thereto.

Referring now to the drawings in which like characters of reference designate corresponding parts throughout the several views, the numeral 1 designates a section of the preferred form of metallic molding 60 having a channel portion 2 and a longitudinally extending transversely curved flange 3, the latter preferably cooperating with the base 4 of the channel portion for holding a longitudinally extending bead 5 65 at one edge of a resilient substantially wedge-shaped weather strip 6.

Heretofore the beads of the weather strips have been inserted by hand between the flanges and bases of the molding, but this 70 has been found to be a rather slow and very tedious operation. With the present invention, the bead 5 of the weather strip is forced between the flange 3 and base 4 of the molding by a machine designated 75 generally by the numeral 7 and that is preferably hand operated.

This machine is preferably mounted upon the top 8 of a suitable table 9 and includes a fixed horizontal support 10 for the molding and a carriage 11 that is adapted to travel along a longitudinally extending guide rail 12 upon one side 13 of the table and that preferably supports a metallic wheel 14 for engagement with the bead 5 85 of the weather strip. The support 10 is preferably in the form of a flat elongated member that preferably extends longitudinally of the table adjacent to the side 13 thereof and is preferably provided at its 90 adjacent side edge with a longitudinally extending lateral projection 15 to which the channel portion 2 of the molding is applied as shown in Figures 5 and 6 respectively. The wheel 14 is preferably rotatively mounted on a horizontal stub shaft 16 journaled in the carriage 11 and is preferably provided with a beveled peripheral portion 17 for engagement with the flange 3 of the molding to hold the said flange 95 spaced from the base 4 while the bead 5 is being forced by the narrow flat peripheral portion 18 of the wheel into position.

For moving the carriage longitudinally 100 of the table so that the wheel will force the bead of the weather strip between the flange 3 and base 4 of the molding, I preferably provide a pinion 19 that meshes with the teeth of a horizontal rack 20 rigidly secured 105 to the side 13 of the table at the upper edge 110

thereof. This pinion is non-rotatively mounted on a shaft 21 journaled in the carriage 11 and is adapted to be driven by a suitable crank 22 connected to the shaft.

5 To facilitate the attachment of the weather strip to the molding, I preferably provide a wedge-shaped arm 23 that projects forwardly from the carriage 11 and that is adapted to spring the flange 3 away from 10 the base 4 to provide a space into which the bead 5 of the weather strip may be readily moved by the wheel 14.

For guiding the weather strip into the path of the wheel 14, I preferably provide 15 an inverted U-shaped bracket 24 that is mounted on the inner face of the carriage 11 in advance of the wheel 14 and that is adapted to receive the wedge shaped portion 6 of the weather strip. One arm 25 of the guide 20 engages the flat side of the weather strip while the other arm is preferably shorter in length and engages the inclined side of the strip above the bead.

25 As a precaution against the molding becoming disengaged from its support, while the wheel 14 travels along the weather strip, I preferably provide a second wheel 26 that is mounted on the shaft 16 in spaced relation to the wheel 14 and that has a flat 30 peripheral portion 27 which is adapted to travel over the uppermost side of the channel portion 2 of the molding.

For automatically ejecting the molding 35 from its support, after the weather strip has been attached thereto, I preferably provide a series of spaced horizontal pins 28 that are preferably slidably mounted in casings 29 secured to the support 10 and that preferably have lugs 30 extending downwardly 40 into inclined slots 31 in a reciprocatory bar 32 slidably mounted in a longitudinally extending groove 33 in the upper face of the support 10. The bar 32 is preferably reciprocated after the carriage 11 has been 45 moved beyond the remote end of the support 10 for the molding and for this purpose a rack 34 projects forwardly from the carriage 11 at the upper end thereof and is adapted to rotate a pinion 35 nonrotatively 50 secured to a stub shaft 36 journaled in bearings 37 upon the top 8 of the table. A pinion 38 is also non-rotatively secured to the shaft 36 at the opposite end thereof and meshes with the teeth of a rack 39 extending 55 forwardly from the bar 32. Thus, rotation of the pinion 35 in opposite directions by the rack 34 will cause the pinion 38 to reciprocate the bar 32 and cause all of the pins 28 to move simultaneously.

60 In use, the weather strip 6 is first laid along the molding so that the bead 5 will be disposed adjacent to the flange 3. The crank 22 may then be operated by hand to move the carriage 11 along the table and cause 65 the wheel 14 to force the bead 5 of the

weather strip between the flange 3 and base 4 of the molding. After the carriage has been moved beyond the remote end of the support 10, the rack 34 will rotate the pinion 35 and will cause the pinion 38 to move the 70 bar 32 forwardly whereupon the pins 28 will disengage the molding from the support 10. When the carriage is returned to normal position, the bar 32 will be moved rearwardly and will cause the pins 28 to be returned to normal inoperative position. 75

While it is believed that from the foregoing description the nature and advantages of the invention will be readily apparent, I wish to have it understood that I do not 80 limit myself to what is herein shown and described and that such changes may be resorted to when desired as fall within the scope of what is claimed.

What I claim as my invention is:—

1. In a machine of the class described, a support for molding, means for separating portions of the molding to receive a portion of a weather strip, and means for moving the portion of said strip between the separated portions of said molding. 90

2. In a machine of the class described, a support for molding, a wedge-shaped member for separating portions of the molding to receive a portion of a weather strip, and means for moving the portion of said strip between the separated portions of said molding. 95

3. In a machine of the class described, a support for molding, movable means for forcing a strip between parts of said molding, and means for guiding said strip into the path of said movable means. 100

4. In a machine of the class described, a support for molding, a member adapted to travel along said support, means carried by said member for attaching a strip to said molding, a pin adapted to eject the molding from the support after the strip has been attached, a reciprocating member adapted to actuate said pin, an element carried by said member, and means adapted to be operated automatically by said element for actuating said reciprocating member. 105

5. In a machine of the class described, a support for molding, means for attaching a strip to said molding, a plurality of pins for ejecting said molding from said support after said strip has been attached, and reciprocatory means for actuating said pins. 115

6. In a machine of the class described, a support for molding, means for forcing a strip between parts of said molding, and means for ejecting said molding from said support after said strip has been attached. 120

7. In a machine of the class described, a support for molding, a member for forcing a strip between parts of said molding, a movable support for said member, means for ejecting said molding from said sup- 125

port after the strip is attached to the molding and means carried by the movable support for actuating said ejecting means.

8. In a machine of the class described, 5 a support for molding, a member adapted to force a strip between parts of said molding, and a movable support for said member.

9. In a machine of the class described, 10 a support for molding, a member adapted to move along said support, and means carried by said member for forcing a strip between parts of said molding.

10. In a machine of the class described, 15 a support for molding and a member adapted to travel along said support having means for forcing a portion of a weather strip between parts of said molding, said member also having means for holding one 20 of said parts separated from the other while the portion of the strip is being forced into position.

11. In a machine of the class described, 25 a support for molding, a carriage adapted to travel along said support, means carried by said carriage for separating parts of said molding, and means also carried by said carriage for forcing a portion of a weather strip between the separated parts of the 30 molding.

12. In a machine of the class described, 35 a support for molding, a carriage adapted to travel along said support, means carried by said carriage for attaching a strip to said molding, and means also carried by said carriage for guiding said strip into a position to be engaged by said attaching means.

13. In a machine of the class described, 40 a support for molding, a carriage adapted to travel along said support, means carried by said carriage for attaching a strip to said molding, and a U-shaped member also carried by said carriage for guiding said strip into a position to be engaged by said attaching means.

14. In a machine of the class described, 45 a support for molding, means for attaching a strip to said molding while on said support, and means for automatically ejecting said molding from said support after said strip has been attached.

15. In a machine of the class described, 50 a support for molding, a member adapted to travel along said support, means for attaching a strip to said molding, means for detachably retaining said molding in engagement with said support, and a common support upon said member for both said attaching and said retaining means.

16. In a machine of the class described, 55 a support for molding, a member adapted to travel along said support, means carried by said member for attaching a strip to said molding, and means also carried by said

member for detachably retaining said molding in engagement with said support while said strip is being attached.

17. In a machine of the class described, 70 a substantially wedge-shaped member for separating portions of the molding to receive a portion of a weather strip, and a rotatable element for moving the portion of said strip between the separated portions of said molding.

18. In a machine of the class described, 75 a substantially wedge-shaped member for separating portions of the molding for receiving a beaded portion of a weather strip, a substantially U-shaped member for guiding 80 said strip with respect to the separated portions of said molding, and a movable member for forcing the beaded portion of said strip between the separated portions of said molding.

19. In a machine of the class described, 85 a support for molding, a carriage adapted to move along said support, a substantially wedge-shaped member carried by said carriage for separating portions of said molding 90 to receive a beaded portion of a weather strip, and a rotatable element carried by the carriage adapted to move the beaded portion of said strip between the separated portions of said molding.

20. In a machine of the class described, 95 a support for molding, a carriage movable along the support, an arm projecting from the carriage for separating portions of the molding to receive a portion of a weather strip, and a movable member carried by the carriage having means for forcing said portion of said weather strip between the separated portions of said molding.

21. In a machine of the class described, 100 a support for molding, a member adapted to travel along said support, means carried by said member for attaching a strip to said molding, a pin adapted to eject the molding from the support after the strip has been 105 attached, and a reciprocating member adapted to actuate said pin.

22. In a machine of the class described, 110 a support for molding, a member adapted to travel along said support, means carried by 115 said member for attaching a strip to said molding, a pin adapted to eject the molding from the support after the strip has been attached, a reciprocating bar for actuating said pin, a rotatable element for reciprocating said bar, and an element carried by said member for rotating said rotatable element 120 to actuate said bar.

23. In a machine of the class described, 125 a support for molding, a member adapted to travel along said support, means carried by said member for attaching a strip to said molding, a pin adapted to eject the molding from the support after the strip has been 130 attached, a reciprocating bar for actuating

said pin, and means for reciprocating said bar, said means including racks respectively carried by said bar and said member, a shaft mounted on said support, and pinions carried by said shaft and meshing with the racks aforesaid.

24. In a machine of the class described, a support for molding, a wedge-shaped member movable along the support for separating portions of the molding, a rotatable member movable along the molding for forcing a portion of the weather strip between the separated portions of the molding, said rotatable member also having a beveled portion for holding the portions of the molding separated while the portion aforesaid of the strip is being forced into position.

25. In a machine of the class described, the combination with a table having means for supporting a strip of molding, of means for attaching a weather strip to said molding, and a support for said attaching means movable along the table.

26. In a machine of the class described, the combination with a table for supporting molding, of means for forcing a weather strip between portions of the molding, a support for said means movable along the table, and means for actuating said support.

27. In a machine of the class described, the combination with a table having a ledge for supporting a strip of molding, of means for attaching a weather strip to said molding including an element movable longitudinally of the molding, and a support for said element carried by and movable along said table.

28. In a machine of the class described, the combination with a table for supporting molding, of means for forcing a weather strip between portions of the molding, a support for said last mentioned means movable along the table, a rack carried by the table, and means engageable with the rack for actuating the support.

29. In a machine of the class described, a support for molding including a lateral portion adapted to be embraced by a portion of the molding, and means carried by the support for forcing a resilient strip between parts of said molding.

30. In a machine of the class described, a support for molding, and means for forcing a resilient strip between parts of said molding including an element mounted for rotation above said support.

In testimony whereof I affix my signature.

HERMAN C. MAISE.
